UNITED STATES PATENT OFFICE.

WILLIAM C. MARTINEAU AND CLARENCE R. MARTINEAU, OF ALBANY, NEW YORK.

HASP-MOUNTING.

1,231,278.

Specification of Letters Patent. Patented June 26, 1917.

Application filed October 2, 1916. Serial No. 123,242.

To all whom it may concern:

Be it known that we, WILLIAM C. MARTINEAU and CLARENCE R. MARTINEAU, citizens of the United States, residing at Albany, 5 county of Albany, and State of New York, have invented certain new and useful Improvements in Hasp-Mountings, of which the following is a specification.

Reference may be had to the accompanying drawings, and the reference characters marked thereon, which form a part of this specification.

Our invention relates to hasp-mountings for various kinds of locking devices, and 15 is particularly adapted for the locking devices of the sliding doors of railway cars and the like.

As an example of one form of locking device to which the invention is applicable, 20 reference may be had to U. S. Letters Patent No. 1,149,205, granted to us August 10, 1915.

The principal object of our invention is to provide a strong and durable mounting 25 for the hasp of a locking device, to prevent the escape of the hasp from its pivot, and to reinforce the pivot to better resist the end-thrust of the hasp.

Other objects will appear in connection 30 with the following description.

Figure 1 of the drawings is a plan view of a hasp-mounting embodying our invention.

Fig. 2 is a central vertical longitudinal 35 section of the same taken on the broken line 2-2 in Fig. 1.

Fig. 3 is a side view of the staple-form keeper.

Referring to the drawings wherein the 40 invention is shown in preferred form, 1, is a hasp having at its inner end a pivot-eye, 2. The outer end of the hasp may be provided with the usual aperture, 3, for the bolt or staple of the complementary member of the 45 locking device, not shown.

The hasp, 1, is pivotally mounted upon a supporting-plate, 4, which is provided with bolt-apertures, 5, whereby the plate can be attached to a sliding door or the like. 50 The plate 4, is preferably made of malleable cast-iron, and has cast integral therewith two tubular bosses, 6-7, arranged longitudinally of the plate.

The boss, 6, passes through the pivot-eye,

2, of the hasp, and forms the pivot for the 55 hasp.

To prevent the escape of the hasp from its pivot, and to reinforce its pivotal connection with the plate, 4, we employ a keeper, 8, in the form of a staple, one leg 60 9, of the keeper being inserted through the tubular boss, 6, and its other leg 10, inserted through the tubular boss, 7, with the body of the keeper extending over part of the pivot-eye 2, of the hasp.

The ends of the legs, 9 and 10, of the keeper are upset or riveted upon the under side of the supporting-plate, 4, as shown at 11, in Fig. 2, whereby the keeper is rigidly secured to the plate.

The pivot-eye, 2, of the hasp is formed with sufficient lost-motion to permit the neighboring end of the hasp to abut against the boss 7, which is outside of the eye of the hasp.

The end-thrust of the hasp in the direction of the boss, 7, is thus resisted by both bosses, 6 and 7, as will be seen from Fig. 2.

By having one leg of the staple-form keeper, 8, inserted through the boss, 6, and 80 its other leg secured in rigid relationship to the plate, 4, at a point outside of the pivot-eye, 2, of the hasp, the keeper not only serves to prevent the escape of the hasp from its pivotal connection, but reinforces the pivotal connection formed by the boss, 6, and serves to transmit part of the stress upon the pivot-boss 6, through the leg, 10, of the keeper to the plate, 4, at a point more or less distant from the pivot- 85 boss, 6.

By means of the boss, 7, the plate, 4, is reinforced at its point of connection with the leg, 10, of the keeper, and the stress transmitted through the leg, 10, is better 90 distributed to the plate, 4.

The eye-portion of the hasp is preferably made of such cross-sectional form that it engages the respective bosses, 6 and 7, at points immediately adjacent to the surface of the plate, 4.

The body, 8, of the keeper is necessarily located at a certain distance from the surface of the plate, 4, sufficient to permit the hasp to be swung freely upon the keeper in 105 all directions.

We find it desirable to make the dimensions of the eye of the hasp at the inner end

of the hasp, such that, when the hasp is in locked position, said eye-portion will have practically only the same clearance with respect to the body, 8, of the keeper, as it 5 has in its swinging movements.

This result we are able to accomplish, while preventing the eye-portion of the hasp from engaging the bosses 6 and 7, except at points closely adjacent to their 10 bases and the surface of the plate, 4, by providing the hasp with an annular flange, 12, extending around its eye-portion whereby the height of the eye-portion is substantially equal to the horizontal cross-sectional 15 dimension of the eye-portion, as shown in Fig. 2.

In order to confine the thrust to the body-portion only of the hasp and thus to the base portion only of the bosses, 6 and 7, or similar 20 devices whereby the hasp is pivotally mounted, the outer portion of the flange, 12, is so formed as to taper or retreat from the edge-portions of the hasp bordering the pivot-eye, 2, and bordering the neighboring 25 end of the hasp.

What we claim as new and desire to secure by Letters Patent is—

1. In a hasp-mounting and in combination, a hasp provided with a pivot-eye; a 30 supporting-plate having an integral tubular pivot-boss passing through the eye of the hasp; and a keeper in the form of a staple having one leg passing through the tubular boss and secured to the plate, and its other 35 leg secured to the plate outside of the eye of the hasp.

2. In a hasp-mounting and in combination, a hasp provided with a pivot-eye; a

supporting-plate having two integral tubular bosses, one passing through the eye of 40 the hasp to form a pivot for the hasp and the other located outside of the eye of the hasp; and a keeper in the form of a staple having its legs inserted through the respective tubular bosses and rigidly secured to 45 the plate.

3. In a hasp-mounting, and in combination, a supporting-plate having a pair of integral tubular bosses; a hasp provided with a pivot-eye encircling one of said 50 bosses with sufficient lost-motion to permit neighboring end of the hasp to abut against the other boss; and a keeper having two legs inserted through the respective tubular bosses and secured rigidly to said plate. 55

4. In a hasp mounting and in combination, a hasp provided with a pivot-eye; a pivot passing through the pivot-eye of the hasp; and a keeper overhanging the pivot-eye of the hasp, the hasp being adapted to 60 swing freely upon the pivot and the keeper, and having adjacent to its eye an outwardly extending flange whereby the clearance of the eye-portion of the hasp with reference 65 to the keeper when the hasp is in locked position is substantially the same as its clearance in the swinging movements of the hasp, the outer portion of said flange retreating from the edge-portions of the 70 hasp, whereby end-thrust is confined to the body-portion only of the hasp.

In testimony whereof, we have hereunto set our hands this 21st day of September 1916.

WILLIAM C. MARTINEAU.
CLARENCE R. MARTINEAU.
